UNITED STATES PATENT OFFICE.

JOHN W. SMITH, OF PHILADELPHIA, PENNSYLVANIA.

INTERNAL-COMBUSTION ENGINE.

Application filed November 12, 1921. Serial No. 514,598.

To all whom it may concern:

Be it known that I, JOHN W. SMITH, a citizen of the United States, residing at Philadelphia, county of Philadelphia, and State of Pennsylvania, have invented certain new and useful Improvements in Internal-Combustion Engines, of which the following is a specification, reference being had to the accompanying drawings.

10 My invention relates to internal combustion engines or motors, and is specially concerned with the cooling of such engines to prevent overheating. The principal object of my invention is to accomplish this cooling by means of the atmospheric air in a thoroughly effective and satisfactory manner. The invention is applicable with great advantage to engines for the propulsion of automobiles and air-craft.

20 While many attempts have been made to construct satisfactory air-cooled internal combustion engines, such attempts have hitherto failed of real success, in that the results attained have always been far inferior to those with water-cooling. Through my present invention, I have succeeded in securing an effectiveness of air-cooling equal or even superior to that of water-cooling, and this in a thoroughly convenient and 30 practicable manner, not involving complicated or unduly expensive forms or features of construction. Without as yet attempting to formulate my invention, I may render the following description of the best 35 embodiment of it known to me more readily intelligible by a brief preliminary explanation of the main features of that embodiment.

40 One important feature of the construction here illustrated and described is the provision for cooling the engine cylinders at their zone or region of combustion or explosion,—where the highest temperatures are developed,—by means of highly thermo-conductive cooling structures or elements extended to afford radiating surface that may exceed the area of heat-absorption many-fold. Another important feature is a somewhat similar provision for cooling the 45 exhaust valves (which when open are completely surrounded by the heated products of combustion) by means of a highly thermo-conductive cooling element or structure affording ample area for absorption of heat from and adjacent the valve stem,—though otherwise isolated as far as possible

from the heating influence of the exhaust,—and extended to afford radiating surface that may greatly exceed the area of absorption. The cooling or heat-dissipating action 60 of these elements is supplemented and made more effective by cooling means for dissipating the heat from other portions of the cylinder structure besides the combustion zones and the exhaust valves, and by provisions 65 for assuring ample flow of cooling air over the various radiating surfaces.

Other valuable features and advantages will become apparent as the description 70 proceeds.

In the drawings, Fig. I is a side view of an air-cooled multi-cylinder automobile engine that represents the best embodiment of my invention at present known to me, certain parts being broken away or in section. 75

Fig. II is a cross section of the cylinder structure generally on a larger scale than Fig. I, taken as indicated by the line II—II in Fig. I, except as regards the cylinder heads, where the section is somewhat staggered so as to include both the intake and 80 exhaust valves.

Fig. III is a plan view of a portion of the cylinder structure, with the cover of one of the valve gear housings in horizontal section. 85

Figs. IV and V are respectively a plan view and an elevation of the cylinder block, two of the cylinders being shown in axial section in Fig. V.

90 Fig. VI is a plan view of a portion of a cooling element for the combustion zones of the several cylinders; Fig. VII shows a cross section through the aforesaid element, taken as indicated by the line VII—VII in Fig. VI.

Fig. VIII is a detail section, taken as indicated by the line VIII—VIII in Fig. VII.

Fig. IX is a fragmentary sectional view 100 illustrating certain features of the valve-actuating mechanism and associated parts, taken as indicated by the line IX—IX in Fig. II.

Fig. X is a fragmentary plan view illustrating features of the valve-operating mechanism, taken as indicated by the lines X—X in Fig. II.

Fig. XI is a fragmentary sectional view 110 illustrating details of construction, taken as indicated by the line XI—XI in Fig. III.

In the engine here shown (see Figs. I,

2
 II, III, IV and V), the cylinders 1, 1 are ranged side by side in a row or series along the crank case 10, separated by interspaces 2, 2. From opposite sides of the row of cylinders 1, 1 project integral longitudinal heat-radiating fins 8, and on the fore and aft sides of each cylinder are similar but shorter fins 9. Besides the radiating means 8, 9, there are additional cooling elements 15 at the combustion zones or chambers 11 (which are here the clearances in the upper ends of the cylinders) where the greatest amounts of heat are developed. These cooling elements 15 comprise annular heat-absorbing portions 17 (see, also, Figs. VI and VII) surrounding the combustion chambers, and plate-like heat radiating means 20, 21, of ample surface, connected to the portions 17, at isolated points, by heat-conducting and radiating members or webs 22, 23, 24. As here shown, the annuli 17, 17 are interposed between the main, lower barrel or body portions of the cylinders 1, 1 and the cylinder heads 30, 30, and form the peripheral walls of the combustion zones or chambers 11, in direct contact with the hot gases therein.

In the cylinder heads 30 are the branching intake passages or inlets 35, supplied with the motive fluid by a manifold 45, and the exhaust passages or outlets 36, through which spent products of combustion escape to the exhaust manifold branches 46. The passages 35 and 36 terminate in conical seats 37 and 38 for admission and exhaust valves 39 and 40.

Surmounting the cylinder heads 30 are fixed cooling elements 50, here separated from the heads to permit access and passage of cooling air between, and also to thermally insulate or isolate them from the heating influence of the exhaust passage. Each of these cooling elements 50 has an integral sleeve or hollow boss portion 60 about the large exhaust valve stem 61 that affords amply extended bearing for transmission or absorption of heat from said stem. The lower boss portion 60 extends down around the stem 61 into the exhaust passage or conduit 36, with a gas-tight fit over a minimum zone of contact in the upper wall of the exhaust passage. This lower boss portion of the sleeve 60 not only affords bearing for the stem 61, but also shields or protects it from the exhaust gases by itself absorbing their heat. As shown, the cooling elements 50 serve as housings for enclosing parts of the valve-actuating mechanisms or gear for the respective cylinders, and are made separate from one another, each in upper and lower halves secured together by bolts 53. The cylinder heads 30 have heat radiating fins 41, and the lower housing halves have radiating fins 88 and 89.

Recurring, now, to the cylinders 1, 1, it will be seen from Figs. IV and V that they

are interconnected by fore and aft webs 3 extending the greater part of their length, as well as by base and top flanges 4, 5, 6 and 7. The top flange portions 5 and 6 (which are in effect enlargements or lugs 70 on the intermediate and end webs 3) are bored and tapped to take the bolts 34 by which the cylinder heads 30 and the annuli 17 are secured to the cylinder bodies 1, as hereinafter described. The radiating fins 8 75 extend transversely to the row of cylinders 1, 1 at approximately uniform intervals, some from the opposite sides of the individual cylinders themselves, and some from the outer sides of the webs 3. The outer edges of these uniformly spaced fins 8 being (for the most part) in one straight line, it will be seen that their several heights and surface areas vary in correspondence with the obliquity and extent of cylinder 85 wall served by each. The like is true of the fins 9. In the midst of the top flange portions 5 interconnecting the cylinders are elongated transversely extending apertures 13 for downward passage of air to cool the 90 adjacent finned fore and aft sides of the cylinders 1, 1. The cylinders 1, 1 should be of wear-resisting material (such as gray iron), preferably cast en bloc, as shown, and integral with their various fins, webs, 95 and flanges.

Referring, now, to Figs. I, II, VI, VII, and VIII, it will be seen that the cooling elements 15, 15 for the several cylinders are connected or united in one fore and aft structure or member. This structure comprises a narrow or shallow central portion 16 made up of the narrow annuli 17 and their interconnecting webs 19, which latter are pierced for the reception of the 105 bolts 34 corresponding with those in the cylinder lugs 5 and 6, and are separated by apertures 18 corresponding with the cylinder-block apertures 13.

Since the entire cooling element 15 will generally be made of relatively soft, poor-wearing metal for the sake of highest thermal conductivity, it is usually preferable that if the piston 12 is to overtravel the annulus 17, the latter be made so much larger 110 internally than the cylinder body 1 as not to come in contact with the piston. (See Fig. II.) At a substantial distance on either side, the central portion 16 is flanked by the radiating plate structures 20 and 21, of considerably greater vertical depth or width, extending alongside the row of annuli 17. The isolated webs 23 by which the plate 21 is supported from the structure 16 are individually of the fin-like "stream-line" configuration indicated in Fig. VIII. At the left-hand side of the element 15, some of the thicker webs 22 are merged together or consolidated into much heavier webs 24, which are bored and bushed at 25 to take the spark-plugs 26 120

(Figs. II and VII). From about the same vertical depth or width as the annuli 17, the webs 22, 23 and 24 are widened or flared, at their outer ends (where they join the plates 5 20 and 21), for the sake of greater rigidity and better distribution of heat to the upper and lower edges of the plates 20 and 21. From the outer sides of the plates 20 and 21 project transverse vertically extending radiating fins, 28, 28 (i. e., extending longitudinally of the cylinder like the fins 8 and the webs 22) that serve to amplify the radiating surface and facilitate the dissipation of heat from the annuli 17. In the aggregate, the webs 22, 23 and 24 are of ample metallic cross section to conduct the heat readily and quickly to the plates 20 and 21, and also afford a certain amount of radiating surface of their own. The plates 20 and 20 21 extend outside of and overlap the cylinder heads 30 and their radiating fins 41, longitudinally of the cylinders, at a suitable distance, as well as the cylinder bodies 1, 1 and their fins 8. Thus access of air to both outer 25 and inner faces of the plates 20 and 21 is freely permitted, and also free passage of air along these inner and outer faces to the cylinder fins 8. The cooling elements 15, 15 with their various parts just described are 30 preferably made integral, as by casting them en bloc. They should generally be of the most highly thermo-conductive material that it is feasible to use, particularly aluminum or aluminum bronze.

35 As here shown (see Figs. I, II, and III), all the cylinder heads 30 are united in one member, which has upstanding bosses or webs 33 pierced for the reception of bolts 34 corresponding with those in the webs 19 40 and in the lugs 5 and 6. The heads 30 are separated by apertures 42 corresponding with the apertures 18 and 13. It will be observed that the intake passages 35 of adjacent cylinders merge for connection to the 45 branches of the intake manifold 45, while each of the exhaust passages 36 is connected to a separate exhaust manifold branch 46. Between the exhaust outlets 36, the vertical radiating fins 41 (Fig. II) project from the heads 30 transversely of the row of cylinders, for the purpose of cooling the heads. These fins 41 are vertically aligned with the cylinder block fins 8. The heads 30 are preferably of gray iron cast en bloc.

50 The cooling elements 15 are clamped between the cylinder heads 30 and the cylinder bodies 1 by means of bolts 34 (already mentioned) whose own heads engage the cylinder head bosses 33, and whose threaded lower ends take into the threaded cylinder lugs 5 and 6. Tightness between the annuli 17 and the heads 30 and bodies 1 is insured by interposed gaskets 31 and 32, which are preferably made of highly thermo-conductive soft sheet metal,—such as sheet aluminum about .040" thick. By initially taking up fairly hard on the bolts 34, they may be put under such tension as to assure tightness and close contact at these joints under all working conditions and variations of temperature; for while the aluminum cooling element 15 will expand and contract more than the iron or steel of the bolts, the length of the latter affords ample elasticity for permitting the utmost expansion of the annuli without overstrain of the bolts. The close contact between the elements 15 (with their gaskets 31 and 32) and the cylinder heads 30 and bodies 1 enables the elements 15 to conduct heat away from the abutting surfaces of heads and bodies, so as to assist in keeping these parts cool as well as the combustion zones of the cylinder walls.

55 Still referring to Figs. I, II, and III, it will be seen that the vertical radiating fins 88 that project transversely from the side of the cooling elements 50 nearest the valve stems 61 are aligned with the cylinder head fins 41 and the cylinder fins 8, while the vertical fins 89 that project fore and aft from the corresponding sides of the elements 50 are aligned (or at least those in the group toward the right in Fig. III) with the cylinder fins 9 and the openings 42, 18, and 13 in the intervening parts. In the present instance, only the lower halves of the elements 50 carry the fins 88 and 89. Each cooling element or housing 50 is spaced from the cylinder head 30 by a shoulder 55 on a hollow boss or sleeve 56 (that extends upward from the head 30 through the housing bottom and affords a bearing for the intake valve stem 83), and is secured by a clamp nut 59 screwed on the threaded upper portion of said boss. Each housing 50 is also (in effect) bolted to the cylinder head 30 by standards or columns 76 whose reduced lower ends extend through holes in the housing bottom and are threaded into circular spacing-bosses 79 on the head. These columns 76 serve to support the valve-operating mechanism, as hereinafter described.

60 This mode of mounting the element 50 on the head 30 minimizes direct transmission of heat to the element 50 from said head, and especially from the hot exhaust passage 36. The exhaust valve stem sleeve 61 does, indeed, make contact with the highly heated exhaust conduit 36 and form a direct thermo-conductive metallic connection thereto from the element 50; but this contact and connection is of the minimum area consistent with gas-tightness, as already explained. The cooling elements 50 should generally be of the most highly thermo-conductive metal, 115 such as aluminum or aluminum bronze.

65 The exhaust valve stem 61 should not only be of quite large diameter (as shown, more than one-third that of the head 40), but should preferably be bored out to a small 120

thickness clear down to the valve head 40 and internally threaded, and should have a core 62 of highly thermo-conductive metal (aluminum or bronze),—screwed in as tight as possible to insure good contact,—to assist in conducting the heat away from the head 40 to the sleeve 60. The stem 61 should have as close a working fit in the sleeve 60 as consists with the avoidance of undue friction, 10 to facilitate the transmission of heat.

Referring, still, to Figs. I, II and III, it will be seen that the engine is almost entirely enclosed in a sheet metal casing 90 whose lower portion 91 surrounds the upper 15 half of the crank case 10, and whose upper trunk-like portion 92 envelopes the cylinders 1, 1 and many of the associated parts. The end walls 93 of the trunk 92 extend upward to the plane of division of the cooling elements 50, while the side walls 94 terminate about even with the upper edges of the radiating plates 20 and 21. At the right of the engine (Figs. II and III), the trunk side 20 94 is supplemented or extended upward by a vertical sheet 96, fitting closely and aligned with the radiating plate 21 at its upper edge,—and secured by screws 97 to webs 98 connecting adjacent ends of the fins 88. A little below the lower edges of the radiating 25 plates 20 and 21, the trunk sides 94 are joggled inward with an inclination, at 95. Flow of air for cooling is produced by a turbine fan 105 mounted on the engine shaft 107 in a cowling 110 opening from the left-hand end of the casing 90. (Fig. I.) The inclined moving blades 108 attached to the disk 106 on the shaft 107 cooperate with blades 109 fixed to the interior of the cowling 110, and act to pass the air down 30 through the trunk 91 over the cylinder structures and their cooling means.

Referring, now, to the right-hand side of the engine in Fig. II, it will be seen from the arrows that the air is drawn in between the upper edge of the sheet 96 and the sides of the housings 50, down through the vertical channels formed by plate 96, housing 50, and fins 88, and over and around the exhaust conduits 36; down behind the plate 21 45 through the vertical channels formed by the latter and the cylinder walls in conjunction with the fins 41, webs 23 and the fins 8; on down over and amongst the fins 8, and into the casing 91. Air is also drawn in between the upper edge of the trunk side 94 and the plate 21, down along the outer face of this plate through the vertical channels formed by the plate in conjunction with the trunk side 94 and the fins 28; this air finally 50 issues from the lower ends of these channels and is deflected amongst the fins 8 by the trunk wall offset 95, so as to mingle with the air stream already described. At the left of the engine, the same double air flow 55 occurs,—except for the difference entailed

by the absence of any plate 96 or fins 88. Between the housings 50, air is drawn down through the vertical channels formed by them and their fins 89. At the left, this air is drawn over the intake conduits 35 and behind the plates 21; and toward the right, it is drawn down through the vertical openings 42, 18, and 13 into the vertical channels formed in the interspaces 2, 2 by the adjacent cylinder sides and the fins 9,—finally striking the bottom cylinder flanges 4 and being deflected to right and left out into the casing 91 below the lower ends of the fins 8 and 9 (which terminate about at the lowermost positions of the upper ends of the pistons 12). At either end of the set of cylinders, the air flows down between the trunk ends 93 and the adjacent surfaces of the various parts (50, 30, 15, 1) very much like that entering between the housings 50. 60

Thus the air is caused to flow over the radiating means and surfaces of the various parts and cool them effectively.

Most important to the success of air cooling is the heat-dissipating action of the metallic cooling elements 15 and 50 for the combustion zone and the exhaust valve. By extending these to a sufficient distance from their areas of heat absorption, it is practicable to gain room for amplification of 65 their extensive radiating surfaces to any degree really required; while by directing this expansion or extension of their radiating surfaces longitudinally of the cylinders,—especially in the case of the element 15,— 70 it is possible to keep the cylinder structures compact. It is also important, of course, that these metallic cooling elements be so arranged as to absorb heat adequately 75 from the critical portions of the cylinder 75 structures.

It remains to describe briefly the valve gears or actuating mechanisms, which are in part enclosed in the housings 50,—or one of these mechanisms. As shown in Figs. II and III, the intake and exhaust valves 39 and 40 are urged toward their seats 37 and 38 by concentric helical compression springs 80 and 81, 62 and 63, acting between the bottom of the housing 50 and disks 82 and 64 secured to the upper ends of the respective valve stems 83 and 61. The upper ends of the valve stems 83 and 61 are connected by ball and socket joints with the arms of actuating levers 85 and 66, respectively. These levers 85 and 66 have spherical-bottomed sockets for rocking on hemispherical parts which bear—and are free to slip as required by the rocking of the levers—on the flat ends of the respective adjusting screws 86 and 67, whose upper ends are threaded through an overhanging bracket plate 73 above the levers and have lock nuts 75. 110

The levers 85 and 66 are themselves op- 115

erated (see Figs. II, III, IX and X) by push-rods 70 connected to their other arms by ball and socket joints, and extending down into the crank casing 10 through a tubular casing 71 (of oblong cross-section) whose upper end is clamped to the bottom of the housing 50 by a plate 72 bolted thereto. The push-rod actuated ends of the levers 85 and 66 have flat-faced lugs 87 and 78 by which they are guided in vertical slots or slideways in a web 77 depending from the bracket plate 73. The rods 70 may be actuated by any suitable mechanism, such as cams 115 on the usual cam-shaft 116 in the crank case 10. As shown, the lower ends of the rods 70 have ball and socket connection with plunger heads 120 sliding in ways 121 mounted in a housing 122 bolted at 123, 123 to the upper side of the crank case 10, and these plunger heads 120 carry rollers 124 for engaging the cams 115. The lower end of the casing 71 has a close fit in the upper side of the housing 122. One end of the bracket plate 73 that carries the fulcra 86 and 67 is screwed fast (and secured by a lock nut 125) on the upper end of a supporting column 74 that extends down through the casing 71 to the crank case 10, where it is anchored and supported. The lower end of the column is screwed fast and secured in the housing 122, between the rods 70. The other end of the bracket plate 73 is supported and secured (see Fig. XI) on the upper ends of the two short columns 76, which are anchored and supported on the cylinder head 30 as already described. Thus the bracket plate 73 has a three-point support; at one end, adjacent the push-rods 70, on the column 74 fastened to the crank case, and at the other end, adjacent the valve stems 83 and 61, on the columns 76 fastened to the cylinder head. The column 74 being exposed to the same temperature conditions as the valve-operating rods 70, changes in length of the rods 70 are automatically compensated, and hence do not affect the adjustment of the valves as determined by the setting of the fulcra in the bracket 73. Similarly, the columns 76 are exposed to about the same temperature conditions as the valve stems 83 and 61, so that changes in length of the latter are automatically compensated and do not affect the adjustment of the valves.

Having thus described my invention, I claim:

1. A metallic cooling member for an internal combustion engine comprising a row of narrow annuli with interconnecting webs adapted to form the combustion zone walls of the engine cylinders; and wide radiating structures extending along said row of annuli at either side, separated from the annuli to permit access of air between, but connected to said annuli and their interconnect-

ing webs, at isolated points, by heat conducting and radiating members.

2. A metallic cooling member for an internal combustion engine comprising a row of narrow annuli adapted to form the combustion zone walls of the engine cylinders and separated for passage of cooling air between them; and wide plates, with finned radiating surfaces, connected to and extending along said row of annuli at a distance to either side thereof.

3. The combination with an internal combustion engine cylinder body and head, of an element of highly thermo-conductive material comprising a narrow portion interposed between said body and head to form the combustion zone wall of the cylinder, a radiating plate of extensive surface area located at a distance from said narrow portion, and webs connecting the radiating plate to said narrow portion of said element.

4. The combination with an internal combustion engine cylinder, of a radiating plate of extensive surface area at a distance from the cylinder connected thereto by heat conducting webs spaced apart to afford channels for the passage of cooling air.

5. An internal combustion engine cylinder having external radiating means, and radiating means connected to the combustion zone of the cylinder extending outside of and overlapping said radiating means longitudinally of the cylinder, and separated from the cylinder to permit access of air between.

6. An internal combustion engine cylinder having external radiating means, and radiating means comprising a plate connected by heat conducting and radiating webs to the combustion zone of the cylinder, and extending outside of and overlapping said radiating means and the cylinder head.

7. An internal combustion engine cylinder having external radiating means, and radiating means comprising a plate separated from the cylinder to permit passage of air between extending outside of and overlapping said radiating means and the cylinder head, and connected to the combustion zone of the cylinder at isolated points by heat conducting and radiating webs.

8. In an internal combustion engine, the combination of a row of separated cylinders with radiating means between them and at either side; and radiating plates connected to the combustion zones of the cylinders extending along the row of cylinders at either side outside of and overlapping their radiating means and the cylinder heads, and separated from cylinders and heads to permit access of air between.

9. The combination with an internal combustion engine cylinder, of a plate for dissipating heat from the cylinder extending in an axial direction with reference to the cyl-

- inder and having radiating means including lateral fins flanked by vertical surfaces projecting therefrom in opposed relation.
10. An internal combustion engine cylinder comprising a portion of wear-resisting metal with external radiating means, and a part of softer and more thermo-conductive metal including a combustion zone wall and radiating means connected to said combustion zone wall at isolated points by heat conducting and radiating webs, said last-mentioned radiating means extending outside of and overlapping the aforesaid wear-resisting portion of the cylinder and the cylinder head, but being separated from them to permit access of air between.
11. An internal combustion engine cylinder comprising a portion of wear-resisting metal with external radiating means, and a part of softer and more thermo-conductive metal including a combustion zone wall and radiating means including a plate connected to said combustion zone wall by heat conducting and radiating webs and overlapping the wear-resisting portion of the cylinder.
12. An internal combustion engine comprising separated cylinders with radiating means between them and interconnecting webs, radiating means projecting at either side from cylinders and webs, and radiating means connected to the combustion zones of the cylinders extending outside of and overlapping said latter radiating means longitudinally of the cylinders and separated therefrom to permit passage of air behind the same to the radiating means last above mentioned.
13. In an internal combustion engine, the combination of cylinders with interconnecting webs, radiating fins projecting at either side from cylinders and webs, and radiating means connected to the combustion zones of the cylinders extending outside of and overlapping said radiating fins longitudinally of the cylinders.
14. In an internal combustion engine, the combination of cylinders with interconnecting webs, radiating fins projecting at either side from cylinders and webs, and radiating means connected to the combustion zones of the cylinders extending outside of and overlapping said radiating fins longitudinally of the cylinders; and radiating means surrounding but separated from the cylinder heads affording extended bearing for transfer of heat from the exhaust valve stems and extended radiating surface for dissipating the heat so received.
15. In an internal combustion engine, the combination of separated cylinders with radiating means between them and interconnecting webs, radiating means projecting at either side from cylinders and webs, and radiating means connected to the combustion zones of the cylinders extending outside of
- and overlapping said latter radiating means longitudinally of the cylinders and separated therefrom to permit passage of air behind the same to the radiating means last above mentioned; and valve gear housings on the cylinder heads affording extended bearing for transfer of heat from the exhaust valve stems and extended radiating surface for dissipating the heat so received.
16. In an internal combustion engine, the combination of separated cylinders with radiating means between them and radiating means projecting at either side from the cylinders, and radiating means connected to the combustion zones of the cylinders extending outside of and overlapping said latter radiating means longitudinally of the cylinders and separated therefrom to permit passage of air behind the same to the radiating means last above mentioned; and a common cylinder head member for said cylinders apertured to permit passage of air between them.
17. The combination of a series of internal combustion engine cylinders cast en bloc with provision of longitudinally extending interspaces between them for passage of cooling air and having longitudinally extending heat radiating fins at the exterior and in the interspaces aforesaid, and a radiating element common to said cylinders having apertures registering with the interspaces of the cylinder block and heat radiating fins aligned with those of the cylinders.
18. In an internal combustion engine, the combination with the cylinder and a radiating plate finned on its outer face located at a distance from the cylinder and connected thereto by spaced webs affording a multiplicity of channels for air flow at the inner side of the plate, of a casing enveloping the cylinder and cooperating with the last mentioned fins to form a multiplicity of channels for air flow at the outer side of said plate.
19. In an internal combustion engine, the combination of separated cylinders with radiating means between them and interconnecting webs, radiating means projecting at either side from cylinders and webs, and radiating means connected to the combustion zones of the cylinders extending outside of and overlapping said latter radiating means longitudinally of the cylinders and separated therefrom to permit passage of air behind the same to the radiating means last above mentioned; a casing enclosing said cylinders with their radiating means, and also the aforesaid combustion chamber radiating means; and means for passing cooling air through said casing lengthwise of the cylinders.
20. An internal combustion engine comprising separated cylinders with radiating means between them and interconnecting

webs, radiating means projecting at either side from cylinders and webs, and radiating means connected to the combustion zones of the cylinders extending outside of and

5 overlapping said latter radiating means longitudinally of the cylinders and separated therefrom to permit passage of air behind the same to the radiating means last above mentioned; cylinder heads with intake and exhaust passages therein; valve gear housings surmounting said cylinder heads affording extended bearing for transfer of heat from the exhaust valve stem and having radiating means on the side thereof

10 nearest the latter; a casing enclosing said cylinders with their radiating means, and also the aforesaid combustion chamber radiating means; and means for passing cooling air about said valve gear housings and said cylinder heads and through said casing.

21. In an engine, multiple cylinders cast integral having banks of fins arranged in vertical parallel, and a radiating element joining all the cylinders and amplifying the formation of parallel fins between adjacent cylinders.

22. In an engine, multiple cylinders cast integral having channels between the cylinders and banks of fins arranged in vertical parallel, a radiating element common to all the cylinders and amplifying the formation of parallel fins between adjacent cylinders, and fins extending into said channels.

23. In an engine, multiple cylinders cast integral having banks of fins arranged in vertical parallel, a removable plate member

constituting the combustion chamber, and a continuous radiating element integral with the cylinders to which the removable combustion chamber is connected.

40

24. In an engine, multiple cylinders cast integral having banks of fins arranged in vertical parallel and a continuous radiating surface common to all the cylinders, a plate member constituting a removable combustion chamber applied to said radiating surface, and a removable cylinder head having exhaust and intake valves mounted thereon.

45

25. As an article of manufacture, a bolting plate for superposition upon engine cylinders and having combustion chambers formed therein, heat radiating plates adapted to be vertically disposed when the bolting plate is mounted, vertical fins formed on the heat radiating plate, and fins connecting the latter to the bolting plate.

50

26. As an article of manufacture, a bolting plate for superposition on the cylinders of an engine having heat radiating fins, said bolting plate having openings forming combustion chambers, a heat radiating plate having fins, and fins connecting said heat radiating plate to the bolting plate, the latter being spaced away to overlap the cylinder fins.

55

In testimony whereof, I have hereunto signed my name at Philadelphia, Pennsylvania, this 9th day of November, 1921.

JOHN W. SMITH.

Witnesses:

JAMES H. BELL,
E. L. FULLERTON.
